LEMUEL F. HOWARD, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed November 27, 1922. Serial No. 603,482.

My invention relates to railway traffic controlling apparatus, and has for an object the provision of apparatus for automatically governing a train by means of direct current in the track rails.

I will describe several forms of apparatus embodying my invention and will then point out the novel features thereof in claims.

In the accompanying drawings, Fig. 1 is a view showing in side elevation one form of apparatus embodying my invention. Fig. 2 is a top plan view of the apparatus shown in Fig. 1. Fig. 3 is a view showing a modification of the apparatus shown in Fig. 2. Fig. 4 is a view showing a modification of the apparatus shown in Fig. 1. Fig. 5 is a diagrammatic view showing one form of trackway apparatus and one form of train-carried apparatus, both embodying my invention. Fig. 6 is a view showing another modification of the apparatus shown in Fig. 1.

Similar reference characters refer to similar parts in each of the several views.

Referring first to Figs. 1 and 2, the reference character 2 designates a track rail to which direct current is at times supplied by a battery 3 through a contact 4 of a relay 5. Mounted on the train is a device G for detecting the presence of current from battery 3 in the rail 2, and which device in the form here shown is a generator comprising two field members 6 and an armature 7. Each field member 6 is provided with a shoe 6^a projecting outwardly from the member, one shoe projecting to one side and the other shoe to the other side. The field of the generator G is so disposed that one shoe 6^a is on side of the track rail 2, while the other shoe 6^a is on the opposite side of the track rail. It will be seen, therefore, that when direct current is flowing in the rail 2, so that this rail is surrounded by a magnetic field of force, part of the flux will enter one of the shoes 6^a and will pass through the corresponding field member 6, the armature 7, the other field member 6, and will pass out at the other shoe 6^a. It follows that if the armature 7 is rotating while this flux is present, the generator G will deliver alternating current. In the form of apparatus shown in Fig. 2, the armature 7 is driven constantly and at a fixed speed by a suit-

able prime mover, such as a steam turbine.

The generator may be utilized to govern the train in any desired manner. As shown in Fig. 1, this generator supplies current to an alternating current relay 9, the armature 10 of which controls a valve 11 in a pipe 12, and this pipe 12 in turn governs the brakes in such manner that the brakes will be applied when the valve 11 is open. In this form, then, the train may proceed without retardation as long as it is passing over a track rail 2 which is supplied with direct current, but when the supply of direct current ceases, the generator G will cease to supply current to relay 9, so that valve 11 will open and the brakes will be applied.

Referring now to Fig. 3, the apparatus here shown is the same as that shown in Figs. 1 and 2, except that the armature 7 of generator G is driven by an axle 15 of the train, so that the speed of rotation of armature 7 is proportional to the speed of the train. This form of drive is particularly well adapted for use in connection with apparatus such as that shown in Fig. 4, where in the generator G supplies current to a synchronous motor M, which in turn drives a centrifugal device C. Owing to the fact that the speed of armature 7 is proportional to the speed of the train, it follows that the frequency of the current supplied to motor M will also be proportional to the speed of the train, with the result that the speed of rotation of motor M and centrifugal device C will also be proportional to the speed of the train. The centrifugal device C may be employed in any suitable manner to govern the train.

As shown in Figs. 2 and 3, the armature 7 is journaled in two brackets 8 and 8^a, which are attached to the two field members 6 of the generator G and so serve to maintain the proper spacing between these members as well as to furnish bearings for the armature 7. The brackets 8 and 8^a are preferably of non-magnetizable material, such as brass. The shaft 14 of armature 7 projects beyond the bearings 8^a and is supported in a third bearing 13 which is mounted in any suitable manner on the train.

Referring now to Fig. 5, the reference characters 2 and 2^a designate the track rails of a railway along which traffic normally

moves in the direction indicated by the arrow. These rails are divided by insulated joints 16 into a plurality of successive track sections of which only one section A—B is shown in the drawing. It is understood, however, that in practice each track section will usually be provided with apparatus similar to that illustrated for section A—B. Located adjacent the entrance end of section A—B is a signal S^A, which as here shown, is of a semaphore type adapted to indicate stop, caution, or proceed, according as the semaphore is in the horizontal, the inclined, or the vertical position. The circuits for the control of this signal are not illustrated in the drawing for the reason that they form no part of my present invention, and it is sufficient to say that this signal is controlled in accordance with present day practice through the medium of the track relays which will presently be referred to. The track section immediately to the right of section A—B is provided with a similar signal S^B.

25 Track section A—B is provided with a direct current track circuit comprising a battery 17 connected across the rails adjacent the exit end of the section, and a track relay 18^a connected across the rails adjacent the entrance end of the section. It will be noted that current from battery 17 flows in opposite directions in the two rails 2 and 2^a. Means are also provided for supplying the rails of section A—B with a second direct 30 current which flows in the same direction in the two rails. This current, which I will term the "local" current, is furnished by a battery 20, and the polarity of such current is determined by a pole-changer 21 operatively connected with signal S^B. The local current is supplied to the entire section A—B or to a portion of this section, depending on the condition of track relay 18^B, and for this purpose a resistance 19^a is connected 35 across the rails adjacent the entrance end of the section, a second resistance 19^b is connected across the rails at an intermediate point in the section, and a third resistance 19^c is connected across the rails adjacent the exit end of the section. When track relay 18^B is closed, current from battery 20 passes through pole-changer 21, wire 22, front point 40 of contact 23 of relay 18^B, wire 24, resistance 19^c, thence through the two track rails 2 and 2^a in multiple to resistance 19^a and then through wire 25 and pole-changer 21 to battery 20. When relay 18^B is open the current from battery 20 passes through pole-changer 21, wire 22, back point of contact 23 of relay 18^B and wire 26 to resistance 19^b, thence 45 through the two rails in multiple to resistance 19^a, and back to battery 20, through wire 25 and pole-changer 21.

50 It will be seen, therefore, that when the section immediately to the right of point B

is unoccupied, current of one polarity will be supplied to the rails of section A—B throughout the entire length of this section, whereas when the section immediately to the right of point B is occupied by a car or train, current of the other polarity will be supplied by battery 20 to that portion of section A—B which lies between resistances 19^a and 19^b. In the first instance the current is of what I will term "normal" polarity, and in the second instance it is of what I will term "reverse" polarity.

55 Located immediately in the rear of point A is a train represented by a pair of wheels and axle V. Mounted on this train in front of the forward axle thereof are two generators G^T similar to the generator shown in Figs. 1 and 2; also carried by this train, but in the rear of the forward axle are two other generators G^L, likewise similar to that shown in Figs. 1 and 2. The train is provided with an induction motor relay R comprising a pair of stator windings 28 and 28^a, a rotor 27, and a contact 29 operatively connected with the rotor 27. The two generators G^T are connected in the circuit of stator winding 28, the connections being such that the alternating currents produced by these generators due to current from the track circuit battery 17 are additive, whereas, the alternating currents due to local battery 20 neutralize each other. It follows, therefore, that stator winding 28 receives alternating current due to track circuit current, but not alternating current due to local current in the track rails. The two generators G^L are connected in series in the circuit of stator winding 28^a, and this connection is such that the stator winding receives alternating current due to local current in the track rails, but not alternating current due to track circuit current from battery 17.

60 As shown in Fig. 5, all of the generators G^T and G^L are driven from an axle of the vehicle V, so that the frequency and voltage of the currents supplied to relay R will be proportional to the speed of the train. If desired, however, these generators may be driven by a prime mover, such as a steam turbine, as shown in Fig. 6, so that the frequencies and voltages delivered to relay R will be constant.

65 Assuming that the section immediately to the right of point B in Fig. 5 is unoccupied, it will be seen that when train V enters section A—B both windings of relay R will be supplied with alternating current and the relative polarity of the current supplied to winding 28^a will be normal. This condition will continue as long as the train occupies any portion of section A—B, and so relay R will be energized in normal direction throughout this section. Assuming, however, that the section immediately to the right of point B is occupied, it will be noted

that winding 28^a of relay R will be supplied with current of reverse relative polarity as the train enters section A—B, because the local current supplied to this section is of reverse polarity due to the position of signal S^b. Relay R will, consequently, be energized in reverse direction while the train is between resistances 19^a and 19^b. After passing resistance 19, however, the supply of local current will be discontinued so that winding 28^a will no longer be supplied with current. Relay R will accordingly be de-energized and will remain so until the train enters a stretch of track which is supplied with both track and local currents.

Relay R may be utilized to govern the train in any desired manner. As here shown, this relay controls a light signal comprising three lamps D, E and F, indicating respectively, proceed, caution and stop. This signal is so controlled that the proceed lamp D will be lighted when relay R is energized in normal direction, the caution lamp E will be lighted when the relay R is energized in the reverse direction, and the stop lamp F will be lighted when relay R is de-energized. It is, of course, understood that when I speak of the direction of energization of relay R, I refer to the instantaneous relative polarity of the currents in windings 28 and 28^a.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a track rail carrying direct current, a train provided with a generator having a field disposed to receive magnetic flux due to the direct current in said track rail, means on the train for driving the armature of said generator, and train governing apparatus controlled by the current delivered by said armature.

2. In combination, a stretch of railway track, a railway train, a generator located thereon and having a field and an armature, means located in the trackway for continuously supplying magnetic flux to the field of said generator as the train proceeds through the stretch, means on the train for driving the armature of said generator, and train governing apparatus controlled by the current delivered by said generator.

3. In combination, a stretch of railway track, a railway train, a generator located thereon and having a field and an armature, means located in the trackway for continuously supplying direct magnetic flux to the field of said generator as the train proceeds through the stretch, means on the train for driving the armature of said

generator, and train governing apparatus controlled by the current delivered by said generator.

4. In combination, a track rail carrying direct current, a train provided with two spaced generator field members disposed to receive magnetic flux due to the current in said rail, an armature mounted to rotate in the space between said members whereby alternating current will be produced in said armature due to current in the track rail, and train governing apparatus controlled by current produced in said armature.

5. In combination, a railway train, a generator located thereon and having an armature driven by the running gear of the train, means located in the trackway for supplying magnetic flux to the field of said generator, and train governing apparatus controlled by the current delivered by said generator.

6. In combination, a railway train, a generator located thereon and having an armature driven by the running gear of the train, means located in the trackway for supplying magnetic flux to the field of said generator, a synchronous motor operated by current supplied by said generator, and train governing apparatus controlled by said motor.

7. In combination, a railway train, a generator located thereon and having an armature driven by the running gear of the train, means located in the trackway for supplying magnetic flux to the field of said generator, a synchronous motor on the train supplied with current by said generator, a centrifugal device operated by said motor, and train governing apparatus controlled by said centrifugal device.

8. In combination, a railway track carrying two direct currents one of which flows in opposite directions in the two rails and the other of which flows in the same direction in both rails, a train, two generators mounted in front of the forward axle of said train and having their fields disposed to receive magnetic flux due to currents in the two rails respectively, two other generators carried by the train and having their field disposed in the same manners as the first two generators, means for driving the armatures of said generators, and a train governing relay having two windings supplied with currents by the first and second pairs of generators respectively, the first pair of generators being so connected that their outputs due to the first track current are additive and their outputs due to the second track current are neutralized, while the second pair of generators are connected in the opposite manner.

9. In combination, a stretch of railway track, a railway train, a generator located on said train and having a field and an

armature, means for supplying current to at least one rail of said stretch to supply magnetic flux to said field, means located on the train for driving said armature, and 5 train governing means controlled by current delivered by said generator.

10. In combination, a railway train, a generator located on said train and comprising a field and an armature, means located in the trackway for continuously supplying magnetic flux to said field when traffic conditions are safe but not when traffic conditions are dangerous, means located on the train for driving said armature, and train governing means controlled by current supplied by said generator.

11. In a train control system, the combination of a railway track, a vehicle thereon, said track divided into blocks, means con-

trolled by traffic conditions for energizing 20 the rail of each block, means on said vehicle responding to the current in said rail, means for amplifying the effect from said current by mechanical motion and a device on said vehicle operated by said amplified 25 current.

12. In a train control system, the combination of a railway track, a vehicle thereon, said track divided into blocks, means controlled by traffic conditions for energizing 30 a rail of said blocks, means on said vehicle responsive to the current in said rail, means for amplifying said current by mechanical motion and means for energizing said responsive device by said amplified current. 35

In testimony whereof I affix my signature.

LEMUEL F. HOWARD.
